H. E. WITZ

FURNACE

Filed Nov. 9, 1922

INVENTOR.

Henri Emil Witz
BY *Gifford Bell & Scull* ATTORNEYS.

UNITED STATES PATENT OFFICE.

HENRI EMIL WITZ, OF RHEINLAND BADEN, GERMANY, ASSIGNOR TO THE BABCOCK & WILCOX COMPANY, OF BAYONNE, NEW JERSEY, A CORPORATION OF NEW JERSEY.

FURNACE.

Application filed November 9, 1922. Serial No. 599,763.

To all whom it may concern:

Be it known that I, HENRI EMIL WITZ, a citizen of the Republic of Germany, residing at Stockmannstrasse 158, Oberhausen, 5 Rheinland Baden, Germany, have invented certain new and useful Improvements in Furnaces, of which the following is a specification.

My present invention relates to furnaces 10 in which fuel with a considerable moisture content may be economically burned, and will be best understood from the following description and annexed drawings, in which Fig. 1 is a vertical section of one embodiment of my invention in connection with a chain grate stoker; Fig. 2 is an arrangement, partly in vertical section, of a form of my invention applied to a stepped grate, and Fig. 3 is similar to Fig. 2 showing a modification.

Like reference characters indicate like parts in the several views.

In the arrangement shown in Fig. 1, 10 is a combustion chamber beneath a boiler having tubes 11. A chain grate 12 of the usual construction is arranged to carry the fuel from a hopper 13 toward the combustion chamber 10 in the usual manner. A combustion arch 14 is provided above the forward end of the grate, the arch being terminated at its front by a movable gate 15, provided with a screw and nut 16, whereby the distance between the gate 15 and the upper run of the grate 12 may be adjusted. 35 The usual feed gate 17 is provided to regulate the supply of fuel from the hopper 13 to the grate.

The space between the gates 15 and 17 constitutes a drying chamber 18, provided 40 with an outlet duct 19 connected to a fan, the furnace stack, or the like, so as to create a suction therein.

Beneath the drying chamber 18 and at the lower side of the upper run of the grate 12 is a draft box 20 communicating through separate ducts with an inlet pipe 21 which, in turn, is connected with a part of the combustion chamber 10, preferably the upper portion thereof adjacent the boiler tubes 45 where the combustion of the gases from the fuel on the grate 12 has been substantially completed. A damper 22 is arranged at the front of the draft box 20 so that fresh air 50 may be supplied to the draft box to be mixed

with the gases from the combustion chamber 10 in a regulated amount.

When the illustrative form of my invention shown in Fig. 1 is in use, fuel from the hopper 13 passes under the gate 17 to the grate within the drying chamber. Hot gases 60 from the combustion chamber 10 are drawn through the duct 21 and the draft box 20 and the upper run of the grate into and through the fuel resting thereon and out through the drying chamber 18 and the outlet pipe 19. These heated gases remove the moisture content of the fuel, which, during the drying process, is held back by the gate 15 on the drying area of the grate until the fuel is sufficiently dry to be ignited on the 70 combustion area of the grate 12. By allowing fresh air to pass the damper 22, the proper amount of gases to be drawn from the chamber 10 may be regulated to give the best results.

The arrangement shown in Fig. 2 is similar to that shown in Fig. 1 except that the grate 30 is of the ordinary stepped form, having a dry area 31 to which fuel is supplied by the feed gate 32, this fuel being 80 held back thereon by a gate 33, the height of both of these gates being regulated in the usual manner. Beneath the portion of the grate 31 is a draft chamber 34 connected to an inlet duct 35 connected with a waste gas 85 flue 36, through which a portion of the hot gases from the boiler may be drawn. A branch duct 37 provided with a damper 38 permits fresh air to be admitted to the duct 35.

Above the grate 31 is a drying chamber 39 connected with an outlet duct 40 which, in turn, is connected to a centrifugal separator 46, the outlet of which is connected through a pipe 47 with the inlet side of the 95 fan 41, the exhaust side of which connects through a pipe 42 with the waste gas flue of the boiler. The inlet side of the fan is also provided with a branch duct 43 having a damper 44 and the pipe 40 is provided 100 with a damper 45.

As described in connection with Fig. 1, the fuel on the drying portion 31 of the grate is dried by hot gases drawn from the boiler outlet through the pipe 35 by the 105 fan 41, such gases passing from the box 34 through the fuel and the pipes 40 and 42 to the stack. The gate 35 holds the fuel

2
back until it is properly dried. The dampers 45 and 44 may be utilized to regulate the amount of gases being drawn through the fuel and the damper 38 may be used to regulate the mixture of fresh air with such gases to produce the best results.

The separator 46 in the form shown in Fig. 2 is provided for fuel containing a considerable amount of fine dust which would 10 be drawn out of the fuel and passed directly into the stack, if the separator were not provided. If desired, this separator may be omitted, and the gases passed directly from the pipe 40 into the inlet side of the 15 fan 41.

In Fig. 3 the arrangement is similar to that shown in Fig. 2, except that all of the gases from the combustion chamber of the boiler or the like pass through the dust 20 50 and an air heater 51 into the box 52 and from thence through the drying grate 53 into the drying chamber 54 and the pipe 55, suction being created by a fan 56. The gate 57 holds back the fuel delivered to the 25 grate 53 from the hopper 58 until it is sufficiently dry, when it passes to the combustion area of the grate 59.

In this embodiment of my invention, all of the gases flow through the fuel being 30 dried, but since such gases are usually more than sufficient in volume and heat for such purpose, I abstract some of the heat thereof by means of the air heater 51, so that the air used for combustion on the grate 59 will be

preheated while there still will be sufficient 35 heat in the gases passing through the grate 53 to dry the incoming fuel.

It will be understood that the embodiments of my invention are merely illustrative and that the forms thereof may be 40 widely varied.

I claim:

1. In a furnace, a grate having a fuel-drying area and a fuel-combustion area, a drying chamber above the fuel-drying area, 45 a valve to regulate the flow of fuel from the drying area to the combustion area, and means to pass heated furnace gases upward through the fuel on said drying area.

2. In a furnace, a grate having a fuel-drying area and a fuel-combustion area, a drying chamber above the fuel-drying area, a valve to regulate the flow of fuel from the drying area to the combustion area, and means for passing heated gases from a point 55 of substantially complete combustion in the combustion chamber through the fuel on the fuel-drying area.

3. In a furnace, a grate having a fuel-drying area and a fuel combustion area, a drying chamber above the fuel-drying area, 60 a valve to regulate the flow of fuel from the drying area to the combustion area, means for passing heated furnace gases in regulated amounts through the fuel on said 65 drying area, and means to mix air with the gases before they pass through such fuel.

HENRI EMIL WITZ.
